(57) **CLAIM**

The ornamental design for a drink holder for vehicles, as shown and described.

DESCRIPTION

FIG. 1 is a top, front perspective view of a drink holder for vehicles showing my new design in a first configuration;

FIG. 2 is a bottom, rear perspective view thereof;

FIG. 3 is a top, front perspective view thereof, shown in second configuration;

FIG. 4 is a front view thereof, shown in a first configuration;

FIG. 5 is a back view thereof;

FIG. 6 is a left side view thereof;

FIG. 7 is a right side view thereof;

FIG. 8 is a top plan view thereof; and,

FIG. 9 is a bottom plan view thereof.

The broken lines depict portions of the drink holder for vehicles that form no part of the claimed design;
